UNITED STATES PATENT OFFICE.

CHARLES M. LUNGREN, OF BAYONNE, NEW JERSEY, ASSIGNOR TO THE
SAFETY CAR HEATING & LIGHTING COMPANY, A CORPORATION OF
NEW JERSEY.

MANTLE SUSPENSION.

No. 814,912.

Specification of Letters Patent.

Patented March 13, 1906.

Application filed March 6, 1905. Serial No. 248,513.

To all whom it may concern:

Be it known that I, CHARLES M. LUNGREN, residing at Bayonne, in the county of Hudson and State of New Jersey, have invented 5 certain new and useful Improvements in Mantle Suspension, of which the following is a full, clear, and exact description, such as will enable others skilled in the art to which it appertains to make and use the same.

This invention relates to car-lighting systems, and particularly to means for suspending fragile objects of the nature of incandescent-lamp mantles.

One of the objects thereof is to provide 15 simple and efficient means of suspension for articles of the above nature which will be able satisfactorily to withstand the extremes of temperature to which they are subjected in use.

Another object is to provide durable means 20 of the above type which will be of inexpensive character and simple construction, yet capable of resisting the vibration, shocks, and jars to which a car-lighting system is 25 subjected.

Other objects will be in part obvious and in part pointed out hereinafter.

The invention accordingly consists in the 30 features of construction, combinations of elements, and arrangement of parts which will be exemplified in the device hereinafter described and the scope of the application of which will be indicated in the following claims.

In the accompanying drawings, wherein 35 are shown two of various possible embodiments of my invention, Figure 1 is a sectional elevation of one of the same. Fig. 2 is a similar view of the other thereof.

Similar reference characters refer to similar parts throughout both views.

As tending to cast light upon the general 45 nature of my invention it may here be noted that owing to the proximity of the suspending means of an incandescent-lamp mantle to a source of intense heat the same is subjected not only to wide changes in temperature, but to an excessive degree of temperature at certain stages of its use. Owing to this state of 50 facts, it has been found that many forms of support are cracked, due to the effect of extreme changes in temperature, or are warped or disintegrated on account of the excessive

heat to which they are subjected. Either of the above incidents will result in the breaking of the mantle depending therefrom, as its integrity is dependent upon the preservation of the original shape of the member to which it is secured. Another point which is of interest here as tending to render better understood certain features of my invention is that I have found it to be desirable that the mantle be held in fixed relation to the relatively rigid member from which it depends, as in this manner relative movement of these parts 65 at their junction, with a subsequent likelihood of breaking the mantle, is obviated. The difficulty of the problem presented in constructing an efficient device which will carry a fragile gas-mantle safely and for a 70 sufficient period of time on a running train or car under conditions of ordinary traffic should be obvious.

The defects above indicated are done away with and many practical advantages attained 75 in constructions of the nature of that herein-after described.

Referring now to the drawings, there is shown in Fig. 1 what may be termed a "gas-nozzle" 1, which is formed of any desired 80 material and serves not only to conduct the gas or other fuel to the point of combustion, but also, in this illustrative embodiment, to support the mantle and associated parts. Upon this conduit or gas-nozzle 1 and having 85 a threaded connection therewith is a supporting-spool 2, preferably formed largely of a refractory fibrous material, as asbestos, and abutting against a shoulder 3, formed upon the conduit. Within a groove 4 in the spool 90 2 is tied the upper end of a pendent mantle 5, as by means of an asbestos thread 6. The upper portion of the mantle, which as on account of shrinkage would tend to become loose with reference to the member upon 95 which it is mounted, is held in fixed relation to the adjacent parts of the spool 2, as by means of cement 7, hereinafter described. It may here be noted that the word "cement" is used throughout the following claims in a 100 broad sense, as denoting any material which is adapted to be interposed between the surfaces of two adjacent members and adhere to both of the same, thus connecting them one with another. The cement or paste used 105 preferably comprises a refractory oxid which

will become hard on heating—as, for example, thoria or magnesia, mixed to a cream with a material which will burn out upon being subjected to heat, as glue, or one that will remain 5 and act as a flux, water-glass being an example of the latter class. It may here be noted that the term "spool" is used throughout this description and the following claims as having a broad and somewhat arbitrary 10 meaning to denote any member which is adapted to have secured thereto an incandescent-lamp mantle.

The method of use of the above embodiment of my invention is as follows: The flame 15 being directed downwardly toward the mantle strikes the lower end thereof and rolls back along the sides, thus bringing the same into a highly incandescent state. All jars, moreover, are to a certain extent cushioned 20 by the fibrous spool 2 and any vibration or shock which is transmitted to the mantle 5 will not result in the same being swung against the supporting-spool, as these parts are rigidly held in fixed relation by the cement, as above described. Moreover, the 25 relatively rigid yet somewhat elastic and yielding supporting-spool 2 is unaffected by the heat to which it is subjected and on account of its low heat-conducting powers will 30 not transmit the same to any appreciable degree to the parts supported thereon. Also this spool is impervious to the effects of moisture and is unharmed by the changes in temperature, as well as by the excessive degree 35 of heat to which it is exposed.

It will thus be seen that I have provided means for supporting an incandescent-lamp mantle which are adapted to accomplish the objects set forth and which possess advantages many of which will be apparent from the above description and many of which can be appreciated only by a consideration of the exacting conditions to which the mantle is subjected in practical use. I have found, 40 moreover, that a threaded connection between the spool and the member upon which it is mounted possesses distinct advantages in several particulars, as secure holding and ready detachability. The first cost of the 45 parts is small and the labor required to assemble the same insignificant. Moreover, this mounting is characterized by marked durability and general efficiency under the severe conditions of practical use.

50 In Fig. 2 is shown an embodiment of my invention in which the same is applied to a mantle of a form in common use, adapted for use in connection with an upwardly-directed burner. The spool 8 used in this embodiment is similar in general construction to the 55 spool 2 above described and may be supported in any desired manner, as by an asbestos thread or projecting lugs, the same not being here shown, as it forms no part of the 60 present invention. The means of securing

the upper end of the mantle 9 to the spool are substantially identical to those above described with reference to mantle 5.

It may here be noted that the term "mantle" is used throughout this specification and the following claims in a broad sense as denoting any member adapted upon being exposed to the action of a source of heat to become incandescent and radiate such a considerable amount of light as to adapt the 75 same for use as a source of light.

As many changes could be made in the above construction and many apparently widely different embodiments of my invention could be made without departing from 80 the scope thereof, I intend that all matter contained in the above description or shown in the accompanying drawings shall be interpreted as illustrative and not in a limiting sense. I desire it also to be understood that 85 the language used in the following claims is intended to cover all of the generic and specific features of the invention herein described and all statement of the scope of the invention, which as a matter of language 90 might be said to fall therebetween.

Having described my invention, what I claim as new, and desire to secure by Letters Patent, is—

1. In a device of the class described, in combination, a gas-nozzle provided with a threaded portion, an incandescent-lamp mantle and a single member having the open end of said mantle directly secured to one portion thereof and having a threaded portion engaging with said threaded portion upon said gas-nozzle, whereby said gas-mantle is securely and detachably mounted upon said gas-nozzle and is adjustable with reference thereto. 95

2. In a device of the class described, in combination, a gas-nozzle provided with a threaded portion, an incandescent-lamp mantle and a single member formed of compressed asbestos having the open end of said mantle directly secured to one portion thereof and having a threaded portion engaging with said threaded portion upon said gas-nozzle, whereby said gas-mantle is securely and detachably mounted upon said gas-nozzle and is adjustable with reference thereto. 105

3. In a device of the class described, in combination, a gas-nozzle provided with a threaded portion, an incandescent-lamp mantle and a single fibrous member having the open end of said mantle directly secured to one portion thereof and having a threaded portion engaging with said threaded portion upon said gas-nozzle, whereby said gas-mantle is securely and detachably mounted upon said gas-nozzle and is adjustable with reference thereto. 110

4. In a device of the class described, in combination, a gas-nozzle provided with a threaded portion, an incandescent-lamp mantle and a single member having the open end of said mantle directly secured to one portion there- 115 120 125

5 of and having a threaded portion engaging with said threaded portion upon said gas-nozzle, whereby said gas-mantle is securely and detachably mounted upon said gas-nozzle and is adjustable with reference thereto, said member being provided with an exposed portion adapted to be seized in turning the same.

10 5. In a device of the class described, in combination, a gas-nozzle, a spool of compressed asbestos having a threaded connection therewith and provided with a groove, and a pendent mantle secured directly within said groove.

15 6. In a device of the class described, in combination, a supporting member, and a pendent mantle having a closed lower end and having its upper end cemented into fixed relation with said supporting member.

20 7. In a device of the class described, in combination, a mantle, a supporting member having a groove within which said mantle is tied, and means adapted to hold said supporting member and the adjacent portions of said mantle in fixed relation one with another.

25 8. In a device of the class described, in combination, a mantle, a refractory supporting member to which said mantle is tied, and a refractory adhesive substance inserted between and joining said supporting member and the adjacent portions of said mantle.

30 9. In a device of the class described, in combination, a mantle, a relatively rigid fibrous supporting member, and an adhesive substance inserted between and joining said supporting member and the adjacent portions of said mantle.

35 10. In a device of the class described, in combination, a mantle, a relatively rigid fibrous supporting member to which said mantle is tied, and means adapted to hold said supporting member and the adjacent portions of said mantle in fixed relation one to another.

40 11. In a device of the class described, in combination, a mantle, a refractory fibrous supporting member to which said mantle is tied, and refractory means adapted to hold said supporting member and the adjacent portions of said mantle in fixed relation one to another.

45 12. In a device of the class described, in combination, a fibrous, refractory supporting member, and a pendent mantle having a closed lower end and an upper end cemented into fixed relation with said supporting member.

50 13. In a device of the class described, in combination, a gas-nozzle, an asbestos supporting member secured upon said gas-nozzle and a pendent mantle having a closed lower end opposite said gas-nozzle and an upper end cemented into fixed relation, with said supporting member.

55 14. In a device of the class described, in combination, a supporting-spool of com-

pressed asbestos provided with a groove, a mantle having an end tied within said groove, and an adhesive substance inserted between said spool and the adjacent portions of said mantle and joining the same.

70

15. In a device of the class described, in combination, a gas-nozzle, a spool of compressed asbestos secured thereto and provided with a groove in its outer surface, a pendent mantle having its lower end opposite said gas-nozzle and its upper end tied within said groove, and a refractory adhesive substance inserted between said supporting member and the adjacent portions of said mantle and joining the same one with another.

75

16. In a device of the class described, in combination, a conduit having a threaded lower end and provided with a shoulder, a spool of compressed asbestos threaded upon said conduit and resting against said shoulder, said spool being provided with a groove in its outer surface, a pendent mantle having a closed lower end opposite the open end of said conduit and having its upper end tied within said groove, and a refractory adhesive substance inserted between said spool and the adjacent portions of said mantle and holding the same in fixed relation one to another.

80

17. In a device of the class described, in combination, a supporting member, a conduit having a threaded connection with said supporting member, and a pendent mantle having a closed lower end and having its upper end cemented into fixed relation with said supporting member.

85

18. In a device of the class described, in combination, a gas-nozzle, a spool of compressed asbestos having a threaded connection therewith and provided with a groove in its outer surface, a pendent mantle having its lower end opposite said gas-nozzle and its upper end tied within said groove, and a refractory adhesive substance inserted between said supporting-spool and the adjacent portions of said mantle and joining the same one with another.

90

19. In a device of the class described, in combination, a conduit having a threaded end and a shoulder, a spool of compressed asbestos threaded upon said conduit and resting against said shoulder, and a pendent mantle having a closed lower end and having its upper portions cemented into fixed relation with the lower portion of said spool.

95

20. In a device of the class described, in combination, a gas-conduit, a pendent mantle adapted to coact with said conduit as a source of light, and a single member provided with a groove within which the upper end of said mantle is tied and threaded upon said conduit, said member being provided with an exposed portion adapted to be seized in turning the same relative to said conduit.

100

105

110

115

120

125

130

21. In a device of the class described, in combination, a gas-conduit, a pendent, globular mantle adapted to coact with said conduit as a source of light, and a single resilient member having a depressed portion within which the upper end of said mantle is tied and being threaded directly upon said gas-conduit, said member being provided with

an exposed portion adapted to be seized in turning the same relative to said conduit.

In testimony whereof I affix my signature in the presence of two witnesses.

CHARLES M. LUNGREN.
